(57) **CLAIM**

The ornamental design for a display screen or portion thereof with animated graphical user interface, as shown and described.

DESCRIPTION

FIG. 1 is a front view of a display screen or portion thereof with animated graphical user interface showing a first image of our new design;

FIG. 2 is a second image thereof;

FIG. 3 is a third image thereof;

FIG. 4 is a fourth image thereof; and,

FIG. 5 is a fifth image thereof.

The appearance of the graphical user interface sequentially transitions between the images shown in FIGS. 1-5. The process or period in which one image transitions to another forms no part of the claimed design.

The outer perimeter broken line rectangle in the figures depicts a display screen or portion thereof and forms no part of the claimed design. All other broken lines depict portions of the graphical user interface that form no part of the claimed design. The different stippling in the figures illustrates a contrast in appearance within the claimed design.
